CLAIM

The ornamental design for an exterior light fixture as shown and described.

DESCRIPTION

FIG. 1 is a top isometric view of an exterior light fixture in accordance with the present invention;

FIG. 2 is a bottom isometric view of the exterior light fixture illustrated in FIG. 1;

FIG. 3 is a top plan view of the exterior light fixture illustrated in FIG. 1;

FIG. 4 is a first side view of the exterior light fixture illustrated in FIG. 1;

FIG. 5 is a second side view of the exterior light fixture illustrated in FIG. 1;

FIG. 6 is a bottom plan view of the exterior light fixture illustrated in FIG. 1;

FIG. 7 is a first end view of the exterior light fixture illustrated in FIG. 1; and,

FIG. 8 is a second end view of the exterior light fixture illustrated in FIG. 1.

The broken lines in the figures show portions of the exterior light fixture for reference only and form no part of the claimed design.

1 Claim, 5 Drawing Sheets
